UNITED STATES PATENT OFFICE.

JOHN BLAND, OF CHICAGO, ILLINOIS.

SCREEN.

Application filed November 28, 1924. Serial No. 752,521.

This invention relates to a vibratory screen and particularly to a balanced vibratory screen. It has for one object to provide in a screen in which generally vertical vibration is set up, a balanced construction so that vibration of the screen is as far as possible taken up in the screen itself and not transmitted through to the foundation of the screen or through to the building in which it is located. Other objects will appear from time to time throughout the specification and claims.

In the particular form illustrated herewith two screens are mounted one above the other. They operate together vibrating toward and away from each other, and thus to a very large degree the vibration is taken up within the screens themselves and is not transmitted through the support and foundation.

My invention is illustrated more or less diagrammatically in the accompanying drawing, wherein:

Figure 1 is a side elevation with parts in section;

Figure 2 is a vertical cross section taken on the line 2-2 of Figure 1;

Figure 3 is a view similar to Figure 1 showing a modified form;

Figure 4 is an end view looking at the upper end of the screen with the feeding device omitted;

Figure 5 is an end view of the lower end of the screen.

Like parts are indicated by like characters throughout.

A is a foundation on which the screen is mounted. B B are screen frames, each of which carries a screen cloth or other screening surface B¹. Each of the screens is preferably pivotally mounted at one end on a support C, which support is carried from a foundation A. At its other end each of the screens is mounted for movement in a support which in the form shown is a spring arrangement, a pair of shafts D running through ears D¹ D¹ on the screen and extending into a member D² carried by the frame D.

About the shaft or rod D is a pair of helical springs E, one resting upon the member D² and bearing upon the lower ear D¹ and supporting the lower screen, the other being between the two screens and supporting the upper screen. It will be obvious that many other types of screens and mountings might

be used without departing from the spirit of my invention.

Mounted between the screens, and in the form here shown, adjacent their upper ends is a pair of spring members E. While I have shown two of these members, a different number might be used. Mounted on these spring members E' is a shaft F. This shaft carries one or more fly wheels F¹. They may be out of balance in themselves or they may be provided with one or more adjustable weights F². At one end of the shaft is a belt pulley F³. Mounted on the framework A or at any other suitable point is a motor 70 or other driving means G. By means of the belt G¹ the motor drives the belt pulley F³ and the shaft upon which it is mounted, the shaft being preferably mounted to one side of the spring members, in bearings H H. 75

Although I have shown an operative device, still it will be obvious that many changes might be made in size, shape and arrangement of parts without departing materially from the spirit of my invention; and 80 I wish therefore that my showing be taken as in a sense diagrammatic.

In the form shown in Figures 3, 4 and 5 I is a lower screen box and I' an upper screen box. The upper box is at each end 85 preferably supported from the lower box. At its forward end the lower box is carried on a pair of threaded rods J J. Upon these rods are mounted adjusting nuts J¹ J¹. Extending laterally from the lower box I is a 90 supporting arm J². This arm is perforated at each end and the threaded rods J pass through these perforations. The height of the lower end of the screen may be raised and lowered by adjustment of the nuts J¹. 95 The lower end of the upper screen member is supported from the member J² by means of blocks J³.

At its upper end the lower screen is supported on a spring member K. This member is provided with a thickened central portion K¹ which engages the bottom of the box I. At its two outer ends, the spring member K is carried on columns or supports K² which extend upward from the foundation support A. The spring member E' shown and described in connection with the form shown in Figure 1 is the same as that shown in these figures. The lower end of the spring E' is fastened to the box I and 110 the upper end is fastened to the box I'. The out-of-balance fly wheels, the pulley and

driving belt are the same in each form of the invention.

L is a hopper or other feeding device by means of which material is deposited on the upper end of the upper screen. L¹ is a chute adapted to receive material from the upper screen, and L² is a similar chute adapted to receive material from the lower screen.

- 10 In the form shown in Figure 3 each of the screen boxes contains two screens M. There may be more than this number of screens or there might be only one of them in each box. As I have shown them here, 15 each screen box contains the screens M, and beneath each screen is a pan M¹ which receives the material as it passes through the screens and conducts it to the chute M². M³ is a multiple feeding device provided 20 with a separate chute adapted to deliver material to each screen within the screening machine.

The use and operation of my invention are as follows:

- 25 When the shaft is rotated, being out of balance, it vibrates. This vibration moves the central portion of the spring members laterally, thus bending the spring. When it bends, its vertical height is of course reduced and the screens thus move together. As the rotation of the shaft continues the spring member straightens again and thus becomes elongated and moves the screen frames apart. Thus as rotation of the unbalanced shaft continues, the spring member which carries it is constantly bent and unbent and each time its length is reduced 30 and then increased again. Thus the screen frames are toward and away from each other, each having practically the same amplitude of vibration but each balancing the other. Thus the vibration incident to the 35 operation of the screen is taken up within the screen itself and is not transmitted away 40 elsewhere through the screen support or foundation.

I claim:

1. In combination in a vibratory screen two screens held against longitudinal movement, and means for vibrating them toward and away from each other in balanced relation.
2. In combination in a vibratory screen two screens held against longitudinal movement attached to each other, and means for moving them toward and away from each other, in balanced relation through an equal amplitude.
3. In combination two screens held against longitudinal movement and a flexible element connecting them, and means for imparting transverse vibration to it said means being active upon the flexible element intermediate the screens.
4. In combination two screens, a spring

member joining the two, in combination with means for imparting transverse vibration to said spring member whereby the screens are caused to move toward and away from each other.

5. In combination two screens, a spring member joining the two, in combination with means for imparting transverse vibration to said spring member whereby the screens are caused to move toward and away from each other simultaneously and through an equal amplitude.

6. In combination a pair of screens one being supported and means for supporting the other screen from it, said means including a spring member joining the two, means for imparting transverse vibration to said spring member whereby the screens are caused to reciprocate toward and away from each other.

7. In combination a pair of screens one being supported and means for supporting the other screen from it, said means including a spring member joining the two, means for imparting transverse vibration to said spring member whereby the screens are caused to reciprocate toward and away from each other simultaneously and through an equal amplitude.

8. In a screening device a pair of frames in which is mounted screen means, a vertical element of spring material attached at each end of said frames, means for vibrating said spring member with a generally horizontal amplitude whereby generally vertical reciprocation of the two screen means is effected.

9. In a screening device a pair of frames in which is mounted screen means, a vertical element of spring material attached at each of said frames, means for vibrating said spring member with a generally transverse amplitude whereby reciprocation of the two screen means is effected.

10. In combination in a vibratory screen a pair of screens one mounted above the other, and means for vibrating them vertically toward and from each other.

11. In combination in a vibratory screen a pair of screens one mounted above the other and means for vibrating them toward and from each other in balanced relation.

12. In combination a pair of screens attached to each other and one mounted above the other, and means for moving them toward and from each other simultaneously and through an equal amplitude.

13. In combination a pair of screens one mounted above the other, and means for moving them toward and from each other, said means including a flexible member attached to each of said screens in combination with means for imparting transverse vibration to said member whereby the said movement of the screens is brought about.

14. In combination a pair of screens one

- mounted above the other, and means for moving them toward and from each other in balanced relation, said means including a flexible member attached to each of said screens, in combination with means for imparting transverse vibration to said member whereby the said movement of the screens is brought about.
15. In combination a pair of screens one mounted above the other, and means for moving them toward and from each other simultaneously and through an equal amplitude said means including a flexible member attached to each of said screens in combination with means for imparting transverse vibration to said member, whereby the said movement of the screens is brought about.
16. In combination, a pair of screens mounted one above the other, the lower one being supported and free to have slight vertical movement, means for supporting the upper screen from the lower, said means including a spring member fastened at one end on the lower member and at the other on the upper member, in combination with means for imparting transverse vibration to said spring member whereby the screens are caused to reciprocate toward and away from each other.
- 20 17. In combination a plurality of screens mounted for movement, means for moving them in balanced motion toward and away from each other, said means including a member joining said screens and carrying a part adapted for unbalanced rotary movement whereby the member is flexed and the screens are moved toward and away from each other with said flexure.
- 25 18. In combination two screens one above the other each mounted at one end for pivotal movement and supported at the other end for generally vertical movement, and a pair of vertical members each attached at each end to one of the screens intermediate its ends, in combination with an unbalanced member mounted on said spring members, means for driving the same whereby the spring members are laterally flexed, their vertical height being alternately reduced and increased so as to move the two screens alternately toward and away from each other in balanced motion.
- 30 19. In combination two screens one above the other and means transposing horizontal thrust into vertical movement to vibrate the screens, said means including a flexible member generally vertical and attached to the two, and an out-of-balance part carried by said flexible member and adapted to bend the said vertical member laterally said means being active on the flexible element intermediate the screens.

Signed at Chicago, county of Cook and State of Illinois, this 12th day of November 1924.

JOHN BLAND.
